COMBINATION NON-ELASTIC ADJUSTABLE
HATBAND AND BOW TRIM HATHyman Ferber, Brooklyn, N. Y., assignor to
Wilmor Novelty Co., Inc., Hackensack, N. J.

Application March 10, 1943, Serial No. 478,599

1 Claim. (Cl. 2—183)

This invention relates to new and useful improvements in a combination non-elastic adjustable hat band and bow trim hat.

More particularly, the invention proposes to so construct the hat band and bow trim that it may be applied to hats of various shapes and designs.

Still further the invention proposes to characterize the new band by the fact that it has an open side with straps continuing therefrom. It is proposed that one of said straps be laced through an opening in the other of the straps, and it is proposed that each of the ends of the band be provided with pairs of closely spaced openings outwardly adjacent the sides of said open side of said band, with the ends of the straps being looped through said spaced openings.

With the construction specified in the previous paragraph the straps may be pulled or slackened to adjust the size of the hat band. At the same time the new construction comprises a decorative bow trim for the hat.

Another object of the invention is the construction of a device as mentioned which is simple and durable and which may be manufactured and sold at a reasonable cost.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

Fig. 1 is a side elevational view of a hat provided with a non-elastic adjustable hat band and bow trim constructed in accordance with this invention.

Fig. 2 is a front elevational view of Fig. 1.

Fig. 3 is a front elevational view similar to Fig. 2 but illustrated with the ends of the straps slipped out from the openings in the straps.

Fig. 4 is a plan view of another hat embodying the same invention.

Fig. 5 is a bottom view of the hat shown in Fig. 4.

Fig. 6 is a front elevational view of the hat shown in Figs. 4 and 5 but with the straps slipped out of the openings in the band.

Fig. 7 is a front elevational view of still another hat embodying the same invention.

Fig. 8 is a fragmentary sectional view taken on the line 8—8 of Fig. 7.

The combination non-elastic adjustable hat band and bow trim hat, in accordance with this invention, may be applied to any hat, indicated generally by reference numeral 16, provided the hat has a flexible hat band 11 formed with an open side 12. Straps 13 continue from the sides of the said opening 12. One of these straps is

formed with an opening 14 through which the other one of the straps passes. Each of the ends of the band 11 is provided with a pair of closely spaced openings 15 outwardly adjacent the sides 5 of the said opening 12 of the band 11. The ends 13^a of the said straps 13 are looped through the spaced openings 15, as clearly illustrated in Fig. 2. These looped ends may be pulled to contract the size of the band 11, or they may be let out to 10 enlarge the size of the band. It should be noted that the looped ends 13^a comprise quite a decorative arrangement.

In the particular design of hat shown in Fig. 1, the hat is provided with a pancake type of crown 15 16 having an ornamental button 17 at the center.

In Figs. 4 to 6 another embodiment of the same invention is disclosed. This embodiment distinguishes from the prior form in the construction of the crown 16' of the hat. This crown has 20 a circular back portion 18 and the front portion has several straight sides 19. This hat is provided with a flexible hat band 11 constructed identically to the corresponding hat band in the prior form of the invention. Like parts may be identified by 25 like reference numerals.

In Figs. 7 and 8 still another form of the invention has been disclosed which distinguishes from the prior forms in the construction of the crown 20 of the hat. This crown is of circular form and 30 it is provided with a side insert 21 which gives the crown height. This hat is also provided with a flexible band 11 constructed identical to the corresponding bands in the previous forms of the invention.

35 While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

45 A flexible hat band having an open side and straps continuing from said open side and one of said straps being formed with an opening and the other strap being passed through said opening, each of the ends of said band having a pair of closely spaced openings adjacent the open sides of said band, said straps having their free ends passed through said openings away from said open side and back through said openings towards said open side to have their ends directed 50 towards each other, said openings being of a length slightly less than the width of said straps to pinch the straps together where they pass through the openings to frictionally grip the edges of the straps.

HYMAN FERBER.
